Application November 9, 1945, Serial No. 627,772

7 Claims. (Cl. 129—28)

(Granted under the act of March 3, 1883, as
amended April 30, 1928; 370 O. G. 757)

1

The invention described herein may be manufactured and used by or for the Government of the United States for governmental purposes and without the payment to us of any royalty thereon in accordance with the provisions of the act of April 30, 1928 (Ch. 460, 45 Stat. L. 467).

This invention relates to filing receptacles and more particularly to improvements in followers such as those used for vertical card files.

The follower of the present invention is intended to be shiftably mounted in a filing receptacle for adjustment into a position in which its compressor plate engages the files therein. In a preferred embodiment the follower is adapted in adjusted position to be so locked to the filing receptacle as to preclude at least rearward follower movement and, while locked, to be so operated as to advance its compressor plate toward the engaged files, whereby the files will be compressed and remain in such condition until they are to be removed from the receptacle.

The construction and functions of the follower of the present invention make it well suited to the requirements of files for the cards used in business and other automatic tabulating machines. In such machines it is important that the cards be straight and flat, otherwise the machine may not operate in the desired manner.

Experience shows that cards used in business machines often become bent or warped for various reasons and then, if fed into a machine, interfere with its normal operation. For example, the cards may become bent or warped from handling. The cards will also tend to buckle when exposed to the atmosphere. Loosely arranged cards in a filing receptacle permit air and its moisture to enter the spaces between adjoining cards. This air and moisture is taken up by the cards and causes them to lose their straight and flat condition.

Filing receptacles provided with cards resting on their edges and with a follower embodying the present invention will straighten warped or bent cards and will prevent the warping or buckling of flat straight cards. This end is accomplished by the compressor plate of the follower which is adapted to exert pressure against the cards and maintain them in closely packed condition, the action of the compressor plate being that of a press.

It is, therefore, an object of this invention to provide an improved locking device for securely locking a file follower in any position of adjustment in a filing receptacle to preclude at least rearward movement of the follower.

Another object is to provide a filing receptacle follower which is adapted to compress rapidly the filed material by a natural and efficient manual motion on the part of the operator.

Still another object is to provide a file follower, of the type having shaft and gear connection to file receptacle side wall racks, with a shaft locking device, whereby proper meshing of gears and racks is constantly maintained, the locking device is normally operative to preclude a shifting movement of the follower in at least one direction, the locking device at all times may be quickly and manually set to release the follower for movement in said one direction, and the locking device is manually operable to advance said follower in the opposite direction and at the same time to preclude movement thereof in said one direction.

Another object is to provide a file follower with a mechanism which provides for locking of the follower in adjusted position by spring action under the control of a manually operable member and for release of the follower by manual movement of the member.

Still another object is to provide in the follower a cut-out finger hold to permit holding the filed material upright when compressing or when releasing the follower.

A still further object is to provide a compressor type of file follower which is characterized by its relatively simple and efficient construction, by the ease with which it may be operated, locked and controlled to compress filed material, and which is durable to insure a long useful life.

Another object is to provide an improved card follower for use with a filing receptacle for machine cards, tabulating cards and the like, which deteriorate or warp if not closely packed when filed, the follower being adapted to compress the filed material at a desired pressure and to maintain the compressed condition of the material as long as desired.

Other objects and advantages will be apparent from the following description, the appended claims, and the accompanying drawings, wherein;

Figs. 1, 2 and 3, respectively, are perspective, top plan, and rear elevational views of an embodiment of the invention, the control device thereof being set manually to permit adjustment of the follower toward or away from the illustrated receptacle end wall. In Fig. 1, the rearward section of the card filing tray is not shown for purposes of illustration. In Fig. 2, parts of the receptacle side walls are sectioned or broken away for purposes of illustration. Fig. 3 is partly in section

on line 3—3 of Fig. 2 to illustrate constructional details.

Figs. 3, 4, 5 and 6 are similar views, but indicate successive settings of the control device. Figs. 3 and 4, respectively, show the clutch of the control device in disengaged and engaged settings. In Fig. 4, the card follower is in a locked position, is in engagement with the cards but does not compress the cards. The Fig. 5 setting results from a manual shifting of the control device from the Fig. 4 setting. In the Fig. 5 setting, the cards are compressed and the follower is locked to the receptacle side walls. The Fig. 6 setting results from a manual adjustment of the control device from the Fig. 5 setting and releases the follower for movement relative to the card receptacle front end wall.

Figs. 7 and 8, respectively, are vertical sectional views taken on lines 7—7 and 8—8 of Figs. 2 and 3.

Fig. 9 is an enlarged detail view of parts shown in Figs. 1 through 8.

Fig. 10 is an exploded view of the mechanism in the control device.

Referring now to the drawings in providing a description of this invention, a filing receptacle A is provided with a follower and compressor B having a control device C.

The filing receptacle A may be of conventional form and construction for holding filing materials D, such as tabulating cards, sheets, photographs, and similar files, which are arranged in vertical position with their edges resting on the filing receptacle bottom. The filing receptacle A (see Figs. 1 and 2) may be in the form of the file drawer or tray having the usual front wall 10, side walls 11, bottom wall 12, and rear wall (not shown). The receptacle A may also be provided with a handle 13 of conventional form for use in carrying the receptacle A when it is removed from its cabinet (not shown).

The inner receptacle side walls are provided with guides, such as the channels 15, set in receptacle side wall recesses, as illustrated in Figs. 1 through 8. The channels 15 serve as tracks for the follower B and extend in parallel relation for the full length of the receptacle A. The depending edge of each channel 15 is in the form of a rack 16. Each rack 16 is spaced from the up-standing edge 17 of the corresponding channel 15.

The follower and compressor B is of relatively simple and yet sturdy construction. The compressor and follower B comprises (note particularly Fig. 3) a relatively flat and stout plate 20 which at its upper and side edges is provided with rearwardly extending flanges 21, 22, 23, 24 and 25. These flanges may be formed by rearwardly bending the corresponding edges of plate stock of which plate 20 is formed or may be in the form of strips welded at their edges to the plate 20. It is preferable that the flanges 21 through 25 be welded together at their meeting edges. The flanges 21 through 25 provide the plate 20 with strength and rigidity. It will be noted that one corner of the follower and compressor plate 20 is provided with a cut-out finger hole bounded by the flanges 23 and 24 to permit holding of the filing material D upright during movement of the plate 20 into and out of engagement with the filing material D. This finger hole is best illustrated in Fig. 3, where it appears in the upper right-hand corner of the plate 20. The cut-out finger hole is also shown in Fig. 1. The follower and compressor B is supported in

the receptacle side wall channels 15 by means of straps 30 which may be attached by rivets or by welding to the flanges 21 and 25 (see Figs. 3 and 9), or may be formed integrally therewith. The central strap section 31 (see Fig. 9) lies flat against, and is secured to, the adjacent plate flange, and the two have aligned openings providing a bearing 32. The opposite ends of each strap 30 are received in the adjacent channel 15 and form two shoes 33 which slidably rest on the inner bottom of the channel 15 (see Fig. 8). The shoes 33 are of such height that they may freely slide in the channel 15, but have negligible freedom for movement between the upper and lower limits of the channel 15. Each strap 30 has angular portions 34 (see Fig. 9) which position the shoes 33 and the central section 31 in spaced vertical planes and extend through the spacing between the edges 16 and 17 of the channel 15 to maintain proper spacing of the strap central section 31 from the adjacent channel 15.

The plate 20 preferably has such width and height that they are but slightly less than the corresponding inner dimensions of the filing receptacle A. It is also recommended that the filing material D to be filed in the receptacle A be of such width and height that such dimensions are slightly less than the width and height of the plate 20. These dimensions are suggested because they secure the best compressing action for avoiding the buckling of the material D during storage in the receptacle A.

The follower and compressor B is provided with and supports a shaft or spindle 40 having a gear 41 on each end thereof. The shaft or spindle 40 is illustrated as having a square cross section and a twist so that its side edges have a helical form. Thus the shaft or spindle 40 may be formed of stock which is square in cross section, which has four flat sides, and which is twisted into the illustrated helical shape. In the illustrated form of the shaft or spindle 40, it has for purpose of illustration a 90-degree twist intermediate its ends. Each square end of the shaft or spindle 40 fits into a correspondingly shaped opening in a gear 41 to preclude relative rotational movement. Each gear 41 has a collar 42 which is journaled in the corresponding bearing 32. Thus each gear 41 is rotatively supported by a bearing 32 which is in turn supported by the shoes 33 that are slidably mounted in the tracks or channels 15.

It will now be seen that the follower shoes 33 maintain vertical stability of the follower plate 20 and maintain at all times the gears 41 in proper mesh with the teeth of the racks 16. The illustrated construction permits limited free transverse motion of the plate 20 from side to side of the receptacle A while maintaining it in a vertical plane to preclude rocking or jamming of the gears 41 and the shoes 33. As the follower and compressor B is shifted relative to the receptacle front wall 10, the gears 41 retain their mesh engagement with the racks 16 and maintain the plate 20 parallel to the receptacle front wall 10 and to the material D filed therebetween. The straps 30, with their shoes 33, assist in retaining the plate 20 at right angles to the receptacle side walls 11 both when the follower and compressor B is in a state of rest and when it is being shifted toward or away from the receptacle front wall 10.

The locking and compressing control device C comprises a sleeve 50, a hand hold block 51, a spring 52, and a collar 53. This control device is in the form of a unit which is mounted on and

supported by shaft or spindle 40. The sleeve 50 and the shaft 40 have helical interfitting connection which in the illustrated construction is secured by providing the sleeve 50 with a through hole which is square in cross section and which axially is formed to generate a helical shape corresponding to the helical shape of the shaft 40. Thus the sleeve 50 is adapted to slide freely back and forth on the spindle 40 in the axial direction. However, the helical interfitting connection between the sleeve 50 and the shaft 40 provides for their relative rotational movement during their relative axial shifting movement. Axial shifting movement of the sleeve 50 from right to left (looking at Fig. 4), while the sleeve 50 is held against rotation, will produce rotary movement of the shaft 40 in such direction as to cause the gears 41 to travel along the racks 16 and toward the front wall 10 of the receptacle A. This last described rotary movement for the gears 41 is in a clockwise direction (looking at Fig. 8). This co-action of the sleeve 50 and the shaft 40 may be secured by a helical interfitting connection of types other than that shown. For example, the shaft 40 may be in the form of a round rod having a helical groove cut or otherwise formed therein to receive a key extending inwardly from the surface of a circular bore in the sleeve 50.

The sleeve 50 is also provided with a shoulder 54 having clutch teeth 55 (see Figs. 3 and 10).

The hand hold block 51 serves as a housing for the sleeve 50, the spring 52 and the collar 53 (see Figs. 3 and 10 for example). The hand hold block 51 is provided with two axially aligned bores 56 and 57 of different diameters corresponding respectively to the two outer diameters of the sleeve 50 and its shoulder 54. The sleeve 50 and the block 51, when assembled as illustrated, are adapted to have relative rotation as well as limited relative axial movement. That is, the sleeve 50 is journaled in the hand hold block 51 and the two are adapted to have limited relative sliding movement in an axial direction. The inner end of the collar 53 is provided with clutch teeth 59, is adapted to fit into the outer end of the bore 57, as illustrated in Fig. 3, and is secured to the hand hold block 51 in fixed position by a set screw 58 (shown in Fig. 1). It is apparent that the removability of the collar 53 facilitates disassembly of the control device.

The spring 52 is received in the larger bore 57 of the hand hold block 51 and is positioned between the counterbore shoulder 60 of the hand hold block 51 and shoulder 54 of the sleeve 50, as shown, for example, in Fig. 3. The action of this spring 52 is to urge yieldingly the block 51 and the sleeve 50 axially in opposite directions to maintain yieldingly the teeth 55 on the sleeve shoulder 54 in engagement with the teeth 59 on the collar 53. The sleeve teeth 55 and the collar teeth 59 act as a clutch which is normally held in its active setting by the spring 52 (see Figs. 4 and 5), but which may be set in disengaged condition by manually shifting the block 51 against the action of the spring 52 and relative to the sleeve 50 (see Figs. 3 and 6).

The hand hold block 51 has an up-standing wall portion 60' (see Figs. 3 and 7), at the upper limit of which is a projecting flange 61 having its outer edge shaped to provide a separate rest 62 for each of several fingers. The flange 61 (see Fig. 7) is at a level slightly below the level of the plate flange 22, and the finger rest 62 is positioned slightly beyond the outer edge of the

flange 22 (see Figs. 2 and 7). This arrangement offers the advantage that the operator may rest the palm of his hand on the flange 22, place his fingers in the recesses of the finger rest 62 and then slide his hand along the flange 22 to secure a corresponding movement of the hand hold block 51.

A kick-out sleeve 63 (see Figs. 1, 2, 3 and 10, for example) is mounted on the shaft 40. The sleeve 63 may be secured to the shaft 40 in the position illustrated in Fig. 3, or the sleeve 63 may be freely rotatable on the shaft 40. In the illustrated embodiment of this invention, the sleeve 63 is freely rotatable on and freely shiftable axially of the shaft 40. The sleeve 63 has such length (as shown in Fig. 3, for example) that it may abut the follower plate flange 25 and have its outer end extend somewhat beyond the plate flange 23. The outer end of the sleeve 63 also is provided with an outer diameter somewhat smaller than the inner diameter of the collar 53. Thus the sleeve 63 serves as a stop for the sleeve 50, when the latter is shifted to the right (looking at Fig. 3). With the sleeve 50 abutting the sleeve 63, as shown in Fig. 3, the hand hold block 51 may be manually shifted to the right until it engages the follower plate flange 23 for disengaging the clutch teeth 55 and 59. This clutch disengagement may be conveniently maintained by manually grasping in one hand both the hand hold block 51 and the follower plate flange 23.

Operation

The most desirable results from the use of the present invention are secured when the receptacle A is to receive cards or other flat filing material D having a length corresponding closely to the inside width of the receptacle A and having such height that when resting with their edges on the receptacle bottom 12, their upper edges are slightly lower in elevation than the upper edge 22 of the compressor plate 20.

Space is provided in the front of the receptacle A for the filing of cards D by shifting the follower B rearwardly, this movement being readily accomplished when the hand hold block 51 is in the clutch disengaging position of Figs. 1, 2 and 3. When the cards D are properly arranged on edge in the receptacle A, the follower B is shifted forwardly, while the block 51 is held in the Figs. 1 to 3 setting, and to the position of Figs. 1 and 2, in which its follower and compressor plate 20 engages the adjacent card D. The cards D are now somewhat closely packed between the receptacle front wall 10 and the plate 20.

The illustrated form of the present invention facilitates one hand operation of the follower B. This hand may be the right hand, which rests on the flange 22 to effect the follower shifting operation and which also engages the hand hold block 51 to maintain the clutch teeth 55, 59 in disengaged condition. During these shifting operations of the follower B with the right hand, the left hand may rest on the left receptacle wall 11 (the wall to the right in Fig. 1) in such position that a finger of the left hand may be positioned in the finger hole provided by the follower plate flanges 23 and 24 to steady the pack of cards D until they are engaged by the follower and compressor plate 20.

When the follower B is advanced into engagement with the cards D, as illustrated in Figs. 1 and 2, the operator may release his hold on the block 51 to permit the spring 52 to shift the block

51 to the left and into the setting of Fig. 4 for effecting engagement of the clutch teeth 59 with the clutch teeth 55. These clutch teeth 55 and 59 are of such shape that the block 51 and the sleeve 50 are precluded from having relative rotational movement in such direction that the gears 41 are locked against rotation in a counterclockwise direction (looking at Fig. 8). That is, with the clutch (55, 59) in the engaged setting, as illustrated in Fig. 4, the follower B is locked to the receptacle side walls 11 to preclude movement of the follower B in a direction away from the receptacle front wall 10. If desired, the clutch teeth 55 and 59 may be of such form that when they are engaged the follower B is locked against movement toward or away from the receptacle front wall 10. If the teeth 55 and 59 are so formed that when they are in engagement they preclude only movement of the follower B away from the receptacle front wall 10, the follower B may be advanced from a rearward position in the receptacle A to a position in engagement with the cards D without it being necessary to operate the block 51 to secure disengagement of the clutch 55, 59.

When the follower B has been advanced to the setting of Figs. 1 through 3 and the control device C has the setting of Fig. 4, the control device C is ready for manual operation to advance the follower B toward the receptacle front wall 10 and thereby compress the cards D. This compressing action is secured by manually shifting the control device C to the left from the setting of Fig. 4 and to a setting such as shown in Fig. 5. During this shifting of the control device C, the clutch teeth 55, 59 are maintained in their engaged condition, there is no relative movement of the sleeve 50 and the block 51, and the control device C moves as a unit axially along the length of the shaft 40. During this shifting movement of the control device C from the setting of Fig. 4 to the setting of Fig. 5, the helical interfitting connection between the sleeve 50 and the shaft 40 causes the shaft 40 and its gears 41 to rotate clockwise (looking at Fig. 8). This clockwise movement of the gears 41 forces them to advance along the racks 16 and thereby cause the follower and compressor plate 20 to press the cards D into a closely packed condition and against the receptacle front wall 10. It has been found that a movement of the control device corresponding to that illustrated by Figs. 4 and 5 is usually adequate to secure adequate compression of the cards D. It is to be noted that throughout the movement of the control device from the Fig. 4 setting to the Fig. 5 setting, the manual pressure on the block 51, as well as the action of the spring 52, maintains the clutch teeth 55 and 59 in engagement and the follower B locked to the receptacle side walls 11, so that the follower B is effectively precluded from rearward movement. Thus in the Fig. 5 setting of the control device C, the follower B is locked in a setting for maintaining the cards D in a tightly compressed condition.

By way of illustration and not of limitation, the helical shape of the shaft 40 and the size of the gears 41 may be so dimensioned that a shifting movement of the control device C from the Fig. 4 position to the Fig. 5 position is effective to advance the follower B a distance of approximately $3/16$ " in its card compressing action. Thus the extent of compressing action of the follower B is variable according to the extent of shifting movement of the control device C from the setting of Fig. 4.

It should be here noted that the operator, in a continuous operation and without removing his hand from the block 51, can shift the control device C from the setting of Fig. 3 to the setting of Fig. 5. In this continued operation the hand hold block 51 of course would pass from the Fig. 3 setting to the Fig. 4 setting before shifting movement of the sleeve 50 is initiated.

It will be noted that when the control device C is being shifted to the Fig. 5 setting, that the hand hold block 51 has a tendency to rotate counterclockwise (looking at Figs. 7 and 8) about the axis of the shaft 40. Such rotary movement of the block 51, however, is precluded by its engagement with the compressor and follower plate 20, as will be apparent from Figs. 7 and 8. Rectilinear movement of the hand hold block 51 when it is shifted to the left (looking at Figs. 4 and 5) is assured by its engagement with the adjacent wall surface of the plate 20.

When access to the compressed card material D is desired, the follower B may be quickly released by a relatively simple and slight movement of the hand hold block 51 from the setting of Fig. 5 and to the right, as illustrated in Fig. 6, for effecting disengagement of the clutch teeth 55 and 59. When the hand hold block 51 is shifted to the right from the setting of Fig. 5 to the setting of Fig. 6, the sleeve 50 remains stationary and the clutch teeth 55 and 59 are disengaged. As soon as these clutch teeth 55 and 59 are disengaged, the sleeve 50 is free to rotate relative to the hand hold block 51 and to permit corresponding rotation of the shaft 40 and the gears 41. With the clutch in the disengaged setting of Fig. 6, the resilience of the compressed cards D tends to shift the follower B slightly in the direction away from the receptacle end wall 10. In this shifting movement of the follower B, the gears 41 will rotate in the counterclockwise direction (looking at Fig. 8) and cause a corresponding movement of the shaft 40 and the sleeve 50.

Figs. 4 and 5 demonstrate an extent of movement required in certain card compressing operations. Figs. 5 and 6 demonstrate, however, that with only a slight movement of the hand hold block 51, the cards D are relieved of the compressing action of the follower B.

As soon as the cards D are relieved of the compressing action of the follower B, the spring 52 tends to reestablish engagement of the clutch teeth 55, 59. Thus it is desirable to shift the control device C to its setting of Fig. 3 for the purpose of shifting the follower B rearwardly to provide greater spacing relative to the receptacle end wall 10 and more convenient access to the cards D.

When the follower B is manually shifted away from the cards D, and the hand hold block 51 is released by the hand of the operator, the control device C may have the setting of Fig. 4 or of Fig. 5, or any other setting along the shaft 40 and between the sleeve 63 and the follower plate flange 21.

The handle 13 and the follower B facilitate removal of the filing receptacle C from its cabinet (not shown) and the carrying of the receptacle to a table or other support. For example, the left hand of the operator may grasp the handle 13 and the right hand may grasp the follower plate flange 22 and the control device finger rest 62, as in a control device operation.

The foregoing is to be understood as merely being by way of illustration, since this invention includes all modifications and embodiments com-

ing within the scope of the appended claims.

We claim:

1. The combination with a filing receptacle and a follower adjustable relative to an end wall thereof, of a mechanism associated with said follower for movement therewith in said adjustment, said mechanism including a shaft and cooperating clutch elements normally in engagement for precluding rotation of said shaft and adjustment of said follower away from said end wall, said shaft and one of said elements having helical interfitting connection, said elements being shiftable rectilinearly as a unit in one direction to rotate said shaft and advance said follower, one of said elements being shiftable in the opposite direction and relative to the second of said elements to effect their disengagement, free said shaft for rotation, and thereby free said follower for adjustment toward and from said end wall.

2. The combination recited in claim 1 in which means are provided for yieldingly maintaining the cooperating clutch elements in engagement.

3. The combination recited in claim 1 in which one of said elements is journaled in the other element, the two elements have opposed toothed faces adapted to be engaged and disengaged by relative movement of the elements axially of said one element, said elements have opposed shoulders, and a spring is disposed between said shoulders for maintaining yieldingly said faces in engagement.

4. In a control device for the follower of a filing receptacle, the combination of manually shiftable means having a finger grip and three aligned bores, an element journaled in the outer two of said bores and having an enlarged section disposed in the other or intermediate one of said three bores, a spring disposed in said intermediate bore and between one end thereof and said enlarged section, the other end of said intermediate bore and said enlarged section having opposed clutch faces normally in engagement with each other by action of said spring, a shaft extending through said element and having helical interfitting connection therewith to provide rotation of said shaft during movement of said element axially thereof, and means for limiting rotary movement of said shiftable means in at least one direction about the axis of said shaft.

5. For use in a filing receptacle, the combination of a follower plate adapted for adjustable movement in the receptacle and relative to an end wall thereof, said plate having a finger receiving through opening extending down from the level of the plate top edge and at one end thereof, a shaft associated with said plate and extending substantially from side edge to side edge thereof and at a level below said plate top edge, a device for controlling said shaft and mounted thereon for adjustment axially thereof, said control device including two clutch parts relatively movable axially of said shaft to effect their engagement and disengagement, means on said shaft and adjacent said plate opening to serve as a limit stop for one of said clutch parts and means interposed between the other of said clutch parts and said follower plate for limiting rotary movement of said other clutch part in at least one direction about the axis of said shaft.

6. In a filing construction including a receptacle having side wall racks, a follower plate adjustable toward and from an end wall of said receptacle, a shaft, gears secured to said shaft and in mesh with said racks, and means slidably mounted in said receptacle and supporting said

plate, said means being so associated with said shaft as to maintain said gears in engagement with said racks; a control device comprising: a sleeve-like element mounted on said shaft for movement axially thereof, said element and said shaft having helically interfitting connection to provide rotary motion of said shaft as said element moves axially thereof, a manually operable element mounted on said sleeve-like element and adapted to have substantially rectilinear movement, opposed clutch faces associated with said elements, means urging said elements in opposite directions axially of said shaft for yieldingly maintaining said clutch faces in engagement to lock said shaft against rotation in at least one direction and thereby lock said follower plate in adjusted position to preclude movement thereof away from said end wall of the receptacle, said manually operable element being shiftable axially of said shaft in one direction to shift said sleeve-like element in the same direction by engagement of said clutch faces and thereby to effect rotary movement of said shaft for advancing said plate toward said end wall to exert pressure on filing material in the receptacle, said manually operable element being shiftable in the opposite direction to separate said clutch faces, remove said pressure, and release said plate for adjustment thereof toward or away from said end wall, said manually operable element in a continued shifting movement in said opposite direction being adapted to shift said sleeve-like element with said clutch faces in separated relation.

7. In a filing construction including a card tray having recessed inner side walls, tracks set in the recesses of said side walls, said tracks each extending between the tray end walls and being provided with a rack extending lengthwise thereof, a follower plate extending between said inner side walls and adjustable toward and from an end wall of said tray, a shaft positioned adjacent and rearwardly of said plate and extending between said inner side walls, a gear secured to each end of said shaft and in mesh with the adjacent one of said racks, and shoes slidably mounted in said tracks and secured to the opposite ends of said plate for supporting the same, said shoes being so associated with said shaft as to maintain said gears in engagement with said racks; a control device comprising: a sleeve-like element mounted on said shaft for movement axially thereof, said element and said shaft having helically interfitting connection to provide rotary motion of said shaft as said element moves axially thereof, a manually operable element mounted on said sleeve-like element and adapted to have sliding engagement with said follower plate in a plane parallel to said shaft axis, opposed clutch faces associated with said elements and encircling said shaft, means urging said elements in opposite directions axially of said shaft for yieldingly maintaining said clutch faces in engagement to lock said shaft against rotation in at least one direction and thereby lock said follower plate in adjusted position to preclude movement thereof away from said end wall of the receptacle, said manually operable element being shiftable axially of said shaft in one direction to shift said sleeve-like element in the same direction by engagement of said clutch faces and thereby to effect rotary movement of said shaft and advance said plate for applying pressure on file material engaged thereby, said manually operable element being shiftable in the opposite direction to separate said clutch faces, remove said

11

pressure, and release said plate for adjustment thereof relative to said end wall, said manually operable element in a continued shifting movement in said opposite direction being adapted to shift said sleeve-like element axially of said shaft with said clutch faces in separated relation.
